Attorney

UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

CABLE CLAMP.

Application filed October 14, 1927. Serial No. 226,108.

My invention relates to a cable support and particularly for supporting a messenger or catenary cable from a cross span wire, or it may be employed for merely connecting 5 together two angularly disposed cables or wires.

The object of my invention is to provide a simple, efficient and easily applied device for holding two angularly disposed cables or 10 wires in fixed relation without injury thereto.

Another object of my invention is to hold such cables in fixed relation, but out of contact or engagement with each other.

15 Another object of my invention is to support one cable from another in such manner that the supporting faces of the device which engage the cables will possess length and conform to the sag or bend of the cables.

20 My invention resides in the new and novel construction, combination and relation of the various parts herein described and shown in the accompanying drawing.

In the drawing:

25 Fig. 1 is a side view in elevation of my invention in assembled relation, but with the parts slightly separated for better disclosing the details.

Fig. 2 is a top view of my invention shown 30 in Fig. 1 and, if rotated ninety degrees, would represent the bottom view of Fig. 1.

Fig. 3 is the inner face view of the lower supporting element in Fig. 1, and also represents the same with respect to the upper 35 supporting element.

Fig. 4 is a top view of the intermediate element shown in Fig. 1.

In the past it has been customary, where 40 two cables are to be secured together in fixed relation and at an angle to each other, to contact the cables with each other and hold them together by some form of clamping means, which would bring great pressure upon the cables to prevent their slipping.

45 This is far from an ideal condition, because the area of contact of two cables crossing each other is very small and the pressure per unit area can be made very high and usually is, which tends to severely distort 50 the cable which is composed of a plurality of wires.

Further, cables secured together as just described are in time liable to take on a slight pivotal action relative to each other, which

means, under the great pressure applied, that 55 there will be a considerable abrasion of the contacting surfaces.

Due to the detrimental results of such a construction, considerable attention has been paid recently to devices for properly holding 60 cables in fixed relation without distorting the cables or injuring them any more than absolutely possible. This is particularly desirous in such construction work as employed in connection with high tension lines, 65 catenary construction of trolley lines, etc.

In my invention I not only maintain the cables in separated relation, but the supporting surfaces thereof are of extended 70 length and the supporting surfaces of the device I employ are such as to prevent the distortion of the cables to any great extent, and also offer a saddle like construction, which conforms to the bend of the cable at the point of connection, thereby preventing 75 injury to the cables at the extreme ends of the saddle.

In my preferred embodiment I employ a lower supporting element 1 and an upper supporting element 2. Each is provided 80 with a saddle portion 3. Each saddle is provided with a groove 4 adapted to fit a cable reasonably close. Each saddle is provided with a straight central portion or seat 5, and the ends are extended into grooved lips 85 6 bent downwardly or upwardly with respect to the elements 1 and 2 respectively. This construction offers a seat for the cable which will conform, to a large degree, with the curvature of the wire and avoid sharp corners on the seat and bends in the cable at the ends of the seat. Each member 1 and 2 is provided with four holes 7 and 7', 8 and 8'. The members 1 and 2 are arranged to be placed assembled with their saddles positioned at ninety degrees to each other, if the cables to be connected are disposed at right angles to each other.

When the members 1 and 2 are positioned in clamping relation, the holes in one member will register with the holes in another member for the reception of the U bolts 9 and 10 inserted into the holes from opposite ends of the device and obliquely disposed with reference to the axes of the cables and also disposed at ninety degrees with respect to each other.

This construction offers a very compact

form of clamping device and the arrangement of the **U** bolts is such as to distribute the clamping strain very uniformly and thereby prevent yielding of the parts with the result that the cables remain permanently in a fixed relation.

In order to prevent the cables contacting with each other, as pointed out, the intermediate member 11 is employed which has two transversely disposed seats 12 of groove shaped formation, and of such length as to correspond with the straight portion or seat 5 of the saddle members.

The extreme ends of the seats 12 are rounded slightly to prevent a sharp edge at this point.

When the device has been installed, it will be appreciated that the member 11 acts purely as a spacer between the cables and also offers an elongated bearing surface, thus reducing the pressure per unit area upon the cable without decreasing the efficiency of the gripping action.

To install my invention it is necessary to remove the nuts from the **U** shaped members and to separate the parts and then the device may be assembled with respect to the cables by first positioning the member 1 with respect to the lower cable to be supported, then positioning the lower **U** bolt 10 in its proper place, then positioning the intermediate member 11 and then the upper clamping member 2, after which the nuts may be applied to the **U** bolt 10 and drawn up until the cables are clamped slightly. The upper **U** bolt 9 is now placed in position and the nuts applied thereto and drawn up and likewise the nuts on the **U** bolt 10 until proper tension has been applied to the parts.

It will be evident that the described method of applying can be varied if desired.

After the device is installed, the upper cable, which rests in the upper seat 4, will support the device and also the lower cable which rests in the seat 4 of the lower clamping element. From this it will be seen that the seat in the upper element conforms to the sag in the upper cable and the seat in the lower element will conform to the sag in the lower supported cable.

By referring to the drawing it will be evident that if the grooved seat in the upper or lower clamping member is rotated about the vertical axis ninety degrees, that the seats in the upper and lower members will be in alignment with respect to a common plane, and if one of the angularly disposed seats in the intermediate member 11 is rotated ninety degrees, these seats will be in alignment, and in that case the device is applicable in holding together in fixed relation two cables which are disposed in the same plane. The clamping of two cables position in the same vertical plane is also common practice in the construction of the

catenary trolley lines and in high tension work, and, therefore, the substance of my invention can be applied for such work also.

There are modifications which will suggest themselves to those skilled in the art, therefore, I wish to be limited only by my claims.

I claim:

1. A clamp for crossed cables comprising a clamping member with a seat therein to receive and rest upon the upper cable, a clamping member with a seat to receive the lower cable and support the same, an intermediate member positioned between the cables and having a seat to receive each cable and means engaging the first two clamping members to draw them, the cables and the intermediate member into clamped and fixed relation. 75

2. A clamp for crossed cables comprising a clamping member with a seat therein to receive and rest upon the upper cable, a clamping member with a seat to receive the lower cable and support the same, an intermediate member positioned between the cables and having a seat to receive each cable and a pair of oppositely disposed **U** shaped bolts positioned in planes angularly disposed to each other to draw the clamping members, the intermediate member and the cables into clamped and fixed relation. 80

3. A clamp for holding two cables in fixed relation comprising a clamping member with a grooved seat therein to receive one cable, a clamping member with a grooved seat to receive the other cable, an intermediate member positioned between the cables and having a grooved seat to receive each cable and means to engage the said clamping members to draw them, the intermediate 100 members and the cables into clamped and fixed relation, said engaging means being arranged to hold said first two clamping members together with their seats either in alignment or crossing. 105

4. A clamp for holding two cables in fixed relation comprising a clamping member with a grooved seat therein to receive one cable, a clamping member with a grooved seat to receive the other cable, an intermediate 115 member positioned between the cables and having a grooved seat to receive each cable and a pair of oppositely disposed **U** shaped bolts positioned in planes angularly disposed to each other to draw the parts and cables into clamped and fixed relation. 120

5. A clamp for holding two cables in fixed relation comprising a pair of oppositely disposed clamping members each having a grooved seat in the inner face, curved and grooved lips from each end of each seat forming a continuation of the said seats, an intermediate member having seats to register and cooperate with the first said seats to receive and grip the cables positioned 125 130

therebetween and means to draw the parts into clamping relation with the cables.

6. A clamp for holding two crossed cables in fixed relation comprising a pair of oppositely disposed clamping members each having a grooved seat in the inner face in alignment with the cables, an intermediate member having seats in alignment with the cables and to cooperate with the adjacent seats in 10 the clamping members to receive and grip the cables in spaced relation, and a pair of oppositely disposed U bolts having their legs

disposed between the crossed cables to draw the parts together in clamping relation with the cables.

7. A cable clamp comprising means to clamp two cables therebetween, and a pair of oppositely disposed U bolts each disposed in a plane angularly disposed to each other and to the planes of the cables.

In testimony whereof I affix my signature.

ARTHUR O. AUSTIN.
